14 Claims. (Cl. 196—14.46)

1

This invention relates to propane-fractionation of lubricating oil stocks. In one of its more specific aspects it relates to a method for the treatment of low asphalt-containing lubricating oil stocks for the separation and recovery of the lubricating oil fractions. In a still more specific aspect it relates to a process for the separation and recovery of lubricating oil fractions from crude lubricating oil stocks containing some asphaltic material by fractionation with liquid propane wherein asphaltic constituents are not precipitated and caked in the treating apparatus.

The asphalt content of a crude oil may conveniently be defined as the per cent of residue from the vacuum distillation of a crude oil having a maximum A. S. T. M. D243-36 penetration of 100 at 77° F. For Oklahoma City crude oils this asphaltic residue constitutes about 2% by weight of the crude oil.

By the term "low-asphalt crude oil" I mean crude oils containing a maximum of about 5% asphalt by weight as determined by the above mentioned A. S. T. M. method. Such a low-asphalt containing crude oil may be distinguished from conventional asphaltic crude oils such as California crudes which contain from 12% to 65% asphalt, and from Wyoming and Arkansas crude oils which contain about 30% asphalt.

Deasphalting petroleum oils and more particularly reduced crude oils from which distillate lubricating oil fractions have been removed is old in the art. Such operations are usually carried out at temperatures between about 70° and 140° F. to take advantage of the precipitating action of propane on the heavy asphaltic constituents of the oil. It has also been recognized for many years that a fractionating effect can be obtained with propane-oil mixtures at temperatures ranging from about 140° F. up to the critical of propane. Utilizing the unique properties of liquid propane whereby increasing temperatures result in progressive rejection of hydrocarbons in such a manner that the higher molecular weight components and the more aromatic and naphthenic components are separated first and the lighter components and more paraffinic hydrocarbons last, a combination of low temperature distillation and solvent extraction is achieved. However, due to the difficulties involved in working at high pressures and in close proximity to the critical temperature of propane, commercial exploitation was unknown until quite recently.

It has been found, however, that some low asphalt-content reduced crude lubricating oil may be fractionated continuously by liquid propane under high pressure and at a relatively high

2

temperature, while other such crude oil stocks can be fractionated only for very short periods of time. In this latter case it has been found that the fractionating equipment became plugged with a deposit of asphaltic material. This asphaltic material has apparently been precipitated from the oil upon contact with the high temperature propane. It should be mentioned that the oils in question were low asphalt-containing oils and did not differ significantly from each other in total asphalt content, as conventionally determined. Why some caused plugging trouble and others did not is not clearly understood.

An object of my invention is to devise a process in which a low asphalt-containing reduced crude lubricating oil stock is fractionated for the separation and recovery of lubricating oil constituents. Another object of my invention is to devise a method for the separation and recovery of lubricating oil fractions from such low asphalt-content crude lubricating oil stocks by fractionation with liquid propane without the formation of hard asphaltic deposits in the oil fractionation apparatus. Still another object of my invention is to devise a continuous process for the removal and production of lubricating oil fractions by fractionation with liquid propane from low asphalt-containing reduced crude oil stocks suitable for the manufacture of lubricating oils, wherein the asphaltic constituents are maintained in such a form that they do not adhere as a hard mass to the fractionation equipment. Still other objects and advantages of the process of my invention will be obvious to those skilled in the art upon reading the following disclosure, which, taken with the attached drawing, forms a part of this specification.

In preparing to apply the above mentioned unique properties of liquid propane to actual commercial fractionation of certain grades of lubricating oils from residual stocks, a hitherto unrecognized problem was encountered. Upon fractionating some Mid-Continent reduced crude lubricating oil stocks with liquid propane in a countercurrent contacting tower at a propane-to-oil volume ratio of about 7:1 with temperatures ranging from about 195° F. at the top to about 175° F. at the bottom of the tower, an SAE 40 oil was continuously separated in the overhead product. On the other hand, when a very similar Mid-Continent reduced crude lubricating oil stock was charged to the process under the same operating conditions a similar fraction of lubricating oil was initially obtained, but the column rapidly filled with a hard asphaltic material in the stripping section thereby making

continuous operation impossible. In this second case, a third phase, that is, a semi-fluid asphaltic phase was apparently produced along with a propane-rich light oil fraction and an oil-rich solution of propane in heavy oil. Upon contacting the charge oil with liquid propane this third phase when first formed was sufficiently fluid to flow nearly to the bottom of the column before the ascending propane had washed it sufficiently to cause it to set to a hard cake. Upon continued 10 operation, this cake builds up in the column until complete closure of the column occurs. Why one low asphalt-containing oil should deposit its asphalt while another low asphalt-containing oil does not when the two oils contain similar 15 amounts of asphalt is not definitely known.

In a study of three well known Mid-Continent crude oils which have long been recognized as excellent sources of lubricating oil stocks, hard 20 deposits were formed when treating two of these stocks with liquid propane while the third was fractionated with propane continuously and without difficulty. It has also been found that some 25 West Texas low-asphalt-content reduced crude oils can be continuously fractionated with propane while others cannot. It is therefore realized that propane fractionation cannot be universally applied to all so-called low-asphalt reduced 30 crude lubricating oil stocks.

I have now discovered that one cause of the 35 deposition of asphaltic material from some low asphalt-containing crude oils when undergoing propane fractionation is a deficiency of the heavy oil, which oil acts in the stripping section of the fractionator to prevent the deposition of a hard asphalt. The present invention overcomes this 40 difficulty by utilizing a recycle of the heavy oils from the bottom of a second propane fractionating column which has for its charge the bottoms from a first propane fractionating column. The 45 bottoms from the second column represent a high concentration of the very heavy oils originally present in the crude oil and the recycling of these bottoms into the stripping section of the first or primary fractionating column increases the proportion of heavy oils sufficiently to prevent the 50 formation and precipitation of the heavy asphaltic phase which plugs the column.

In the drawing Figure 1 represents, diagrammatically, a form of apparatus in which to practice the process of one embodiment of my invention.

Figure 2 represents, diagrammatically, a similar form of apparatus in which to practice the process of a second embodiment of my invention.

Referring now to the drawing, and specifically to Figure 1, a fractionating column 1 is equipped with several pipe connections for inlet of materials entering the process and for outlet of materials leaving this column. Pipes 2 and 10 enter the column at a point somewhat above the midpoint of the column, while line 3 enters the column at a point near its base. Pipe 7 provides for withdrawal of overhead product while pipe 8 permits removal of the bottoms. A second fractionator column 21 is similar in all respects to column 1, this second fractionator having also a charge oil inlet pipe 22, a pipe 23 near the bottom, an overhead product withdrawal pipe 27 and a bottoms withdrawal pipe 28. Column 1 is provided with a heating coil 9 in the top of the column while column 21 also has a coil 29 for heating purposes.

In the operation of my process a reduced crude oil having an initial boiling point of about 850° F.

is prepared by distillation to remove the SAE 10 and 20 stocks. This reduced crude oil containing all crude oil components of SAE 30 and heavier is then fractionated by means of propane to produce an SAE 40 to 50 overhead product, an SAE 70 overhead product and an asphalt-containing heavy oil bottoms product.

This prepared reduced crude oil is charged through the line 2 into the propane fractionating column 1 which has previously been filled with liquid propane under a pressure of about 640 pounds per square inch gauge. The oil feed inlet temperature may vary from about 180° to 200° F. and the contents of the fractionating tower at the feed inlet point is maintained approximately within these temperature limits. Upon contacting the propane within the column at the feed point some of the charge oil dissolves to form a propane-rich phase containing dissolved oil, while 20 some of the charge remains undissolved and tends to settle in the column as an oil-rich phase insoluble in liquid propane. This oil-rich phase, of course, contains some dissolved propane which is acquired during its descent from the feed point 25 to the bottom of the tower. This oil-rich phase accumulates in the bottom of the tower and a sufficient quantity is permitted to remain in the tower so that there will be an appreciable depth of oil as indicated by reference numeral 5. Reference numeral 4 indicates the propane-rich phase which remains above the oil-rich phase, the two phases meeting at the interface 6. Propane is charged into the column through the line 3 and this propane passes upward through the oil-rich phase 5 and strips from this phase oily materials which are soluble in the propane. Upon reaching the interface 6 this propane then enters the propane-rich phase in which it, of course, 30 is completely soluble. The propane-rich phase then ascends through the fractionator and finally reaches the top of the tower. This propane charge stock is introduced into the bottom of the tower at a temperature between the approximate limits of 170° and 190° F. and the bottom of the 35 fractionator is maintained at approximately a temperature between these limits. A heating fluid is passed through the heat exchanger 9 in the top of the tower so as to maintain the propane solution in the top of this fractionator at a temperature between the approximate limits of 190° and 210° F. It will be noted that points higher up the tower are maintained at higher temperatures than lower points in the tower since oils are less soluble in propane at higher temperatures.

The propane passing through the oil-rich phase 5 becomes substantially saturated with oily constituents at the temperature of the bottom of the fractionator. This saturated propane solution then on rising from the interface 6 toward the charge oil inlet point increases in temperature somewhat and this increase in temperature causes a precipitation of the more aromatic and naphthenic and heavier components of the propane solution so that additional oil-rich phase is produced and this additional oil-rich phase, due to its difference of specific gravity from the suspending solution, tends to settle downward and on settling is washed by the ascending current of propane-oil solution.

In the upper section of the tower, the temperature is increased from the feed point to the top which is maintained at the highest temperature of any point in the tower. In this upper section additional heavy oil is precipitated due to its decreased solubility at the higher temperatures and

this heavy precipitated oil also settles downward through the ascending propane solution and this oil is washed of its lighter oil constituents by the propane. By maintaining the temperature at the top of vessel 1 within the limits of about 190° to 210° F. an SAE 40 to 50 grade lubricating oil stock remains in solution in the propane and this material is then passed from the fractionator through the line 7 to a propane separation apparatus, not shown. In this propane separation apparatus, the propane and the oily constituents may be separated by fractionation or any means desired, and the oil recovered therefrom may be passed to a subsequent treating step or to storage, as desired.

The oil-rich phase accumulating in the bottom of fractionator 1 is removed therefrom through the line 8 and this material is then passed as charge stock through exchanger 33 and line 22 into the second propane fractionating column. This column has previously been filled with liquid propane under a pressure of about 460 pounds per square inch gauge. Heating fluid is passed through the heat exchanger coil 29 in the top of the vessel 21 to maintain the propane solution at that point at a temperature between the approximate limits of 140° to 160° F. The propane to this column is added through line 23 at a temperature between the approximate limits of 130° to 150° F. The heat exchanger 33 may in this case be a cooler so that the oil-rich phase removed from fractionator 1 at a temperature between 170° and 190° F. may be cooled to a desirable charge temperature for introduction into vessel 21 so that the temperature at the charge oil inlet point may be held at a value somewhere between the bottom column and the top column temperatures. If the bottom column temperature is, for example, 130° F. and the top temperature 140° F. then the oil from line 22 should be at such a temperature that when mixing with the rising propane solution the average temperature at the charge oil inlet point will be about 135° F. In this manner a substantially uniform temperature gradient may be maintained throughout the length of the column. Sufficient propane is introduced into column 1 through line 3 that the propane-to-charge stock oil ratio may be between the approximate limits of 6:1 and 10:1.

The oil-rich phase withdrawn through line 8 from the bottom of column 1 contains only a relatively small proportion of propane and accordingly only little propane reaches column 21 from this source. Sufficient liquid propane is then introduced into column 21 through the inlet line 23 to maintain the ratio of propane-to-oil in column 21 between the limits of about 6:1 to 14:1. This propane entering column 21 through line 23 passes upward through the oil-rich phase 25 and in so doing strips propane-soluble oils from this phase. By the time the propane reaches the interface 26 the propane is substantially saturated with oils so that the propane-rich solution in the vicinity of the interface 26 is for all practical purposes a saturated solution of oil in propane. This solution then upon rising in the tower 21 becomes heated and this heating reduces the solubility of the heavier oily constituents and of the more asphaltic and aromatic constituents so that these materials then become precipitated as an insoluble oil phase suspended in the propane solution. At points below the oil feed inlet point this newly formed oily precipitate may unite physically with the oily material from the

charge oil which is insoluble in the propane solution at the conditions at the charge oil inlet point. Thus, there exists in this section of the tower a relatively high concentration of heavy oily material and under these conditions asphalt is not precipitated but remains in solution in this heavy oil. This asphalt-containing heavy oil then accumulates in the bottom of the tower as the oil-rich phase 25 and this material is removed then through the bottoms draw-off line 28. I have found by dividing the stream of oil-rich phase passing through line 28 and passing a portion through line 30 and under influence of pump 31 on through line 10 into the primary fractionating column at about the crude oil charge inlet point, that I am able to maintain a sufficiently high concentration of heavy oily material in the section of vessel 1 below the feed point so that the hard asphaltic material is not precipitated. The oil flowing through line 28 of Figure 1 is divided so that from 10 per cent to 50 per cent of this oil-rich phase is passed through line 30 under the influence of pump 31 and on through line 10 into column 1 at about the oil feed point.

By maintaining the temperatures in column 21 somewhere between the above given temperature limits the propane solution leaving the column through overhead line 27 contains oily materials having an average SAE grade of about 70. This propane solution may then be passed to an oil recovery system not shown, in which the oil and propane are separated and from which the oil may be passed to further treating steps or to storage, as desired. The recovered propane from the overhead product of column 21 and the propane from the overhead product from column 1 are, of course, recycled to the system. It is not necessary in both of these columns to maintain the pressures at the exact value given, the main point, of course, being that the column should be operated under sufficient pressure to maintain the propane as a liquid or dense phase under all temperature conditions. As a safety factor, it may be advisable to operate these columns at a pressure about 40 to 50 pounds per square inch gauge greater than the vapor pressure of propane at the highest temperature in the columns.

The portion of the oil-rich phase from line 28 which is not recycled to the feed point of column 1 may be withdrawn from the system through line 32 and passed to a propane recovery system in which a relatively small amount of dissolved propane is recovered from the heavy oil. However, this oil-rich phase withdrawn through line 32 may, if desired, be subjected to fractionation in still another propane column operated under such conditions as to produce, for example, an overhead oil of SAE 90 to SAE 250 grade. After the system has been operated sufficiently long to acquire an equilibrium condition the amount of heavy oil in the oil phase removed from the system through line 32 is equal to the heavy oil content charged to the system through line 2. In this manner the oil recycle is kept constant. In order to facilitate mixing of the charge stock to column 1 with the heavy oil recycled from column 21 to column 1, the reduced crude charge stock may be introduced into line 10 through a branch inlet, not shown. This feature is subsequently discussed in connection with Figure 2.

Specific examples

As an example to show that addition of heavy oils will change the phase relationships sufficiently to prevent asphalt deposition, tests were made

on topped crude oils and mixtures of topped crude oils and bottoms from a propane fractionation step in which SAE 70 oil was taken overhead. The primary fractionation step in which asphalt commonly precipitates was so operated as to take an SAE 50 oil overhead.

Tests were made in a single stage propane fractionation operation in which feed plate conditions of a countercurrent column were approximated and the resulting asphalt deposited under equilibrium conditions was quantitatively measured. The reduced crude oil and propane were charged into a rocking autoclave of one liter capacity and the conditions of temperature and pressure were so controlled that during the test an extract was made at the conditions existing at the point of crude oil inlet to a countercurrent fractionator. At the end of approximately one hour under these test conditions in which the autoclave was continuously rocked, the test was stopped and nitrogen gas was used to displace the contents through an eduction tube which extends to the bottom of the autoclave. Test pressure and temperature were maintained until the sample was completely removed. Following sample removal, the interior of the autoclave was visually inspected for asphalt deposits. The autoclave was then washed with benzene and the washings collected. The benzene was evaporated from the washings and the residue was weighed. The asphalt content of this residue was determined as material insoluble in hexane. The following test results were obtained.

yielded an appreciable amount of asphalt in the autoclave. This oil gave 0.91% of deposited asphalt based on the weight of oil charged to the autoclave. When 50% of a Burbank bottoms from an SAE 70 propane fractionation were mixed with 50% of Burbank reduced crude oil and tested in the autoclave no visual deposition of asphalt could be found. The hexane insoluble material amounted to only 0.05% based on the Burbank reduced crude oil charge in this test. When 75% of Burbank reduced crude oil was mixed with 25% Burbank bottoms from an SAE 70 propane fractionator and the mixture tested in the autoclave, only a slight asphalt deposit could be seen in the autoclave. Hexane insoluble material was 0.13%. Such mixtures of Burbank reduced crude with the Burbank bottoms could be charged to a primary propane fractionator, taking a 40 to 50 oil overhead in continuous operation without asphalt deposition in the section of the fractionator below the feed point.

The apparatus of Figure 2 used for practicing the process of a second embodiment of my invention is similar in many respects to the apparatus illustrated in Figure 1. This apparatus of Figure 2 includes fractionating columns 41 and 46. To column 41 are connected an overhead product line 44, a bottoms withdrawal line 45, a line 43 for introduction of liquid propane, and a line 49 for introduction of charge and recycle oils. To column 46 are connected an overhead product withdrawal line 47, a bottoms withdrawal line 60, a propane inlet line 48 and a feed inlet line 45.

	Pressure P. s. i. g.	Temp. °F.	Propane/ Oil Ratio	Autoclave Washings				Visual Observation
				Total Grams	Oil, Grams	Asphalt, Grams	Percent Asphalt Chg. Basis	
West Edmond (Okla.) Reduced Crude which did not Plug a Column.	640	180	6.4:1	0.86	0.76	0.03	0.02	No Asphalt.
Andector (Texas) Reduced Crude which did not Plug a Column.	640	180	6.4:1	1.67	1.55	0.02	0.02	Do.
Oklahoma City Reduced Crude which plugged a Column.	640	180	6.4:1	2.44	1.97	0.39	0.30	Asphalt Present.
Burbank Reduced Crude which Plugged a Column.	640	180	6.4:1	4.53	3.16	1.18	0.91	Do.
50% Burbank Reduced Crude 50% Burbank Bottoms from SAE 70 Run.	640	180	6.4:1	2.12	2.05	0.06	0.05	No Asphalt.
75% Burbank Reduced Crude 25% Burbank Bottoms from SAE 70 Run.	640	180	6.4:1	3.16	2.85	0.17	0.13	Small Amount of Asphalt.

All of the above tests were carried out at a temperature of 180° F. under pressure of 640 pounds per square inch gauge and at a propane to oil ratio of 6.4:1. In the first test a West Edmond, Oklahoma, reduced crude oil was tested. This crude oil, when tested in a continuously operated pilot plant propane fractionation column, did not give an asphalt deposit at points below the feed point. When the autoclave was operated under feed plate conditions for removal of an SAE 40 to 50 overhead lube stock it will be noted that this crude oil also gave no asphalt deposition on the interior surface of the autoclave. Similarly, an Andector, Texas, reduced crude oil which did not plug with asphalt a pilot plant column, also did not give asphalt deposition in the autoclave. An Oklahoma City reduced crude oil sample which did give asphalt deposition and plugging of a pilot plant column also gave some deposited asphalt in the autoclave. The test results of the table indicate that 0.30% of asphalt was deposited, based on the oil charged to the autoclave. A Burbank, Oklahoma, reduced crude oil which also plugged a pilot plant fractionation column

Both columns are provided with slats or baffles for promotion of more efficient liquid-liquid contacting. Heating coils 52 and 53 are situated in the upper portion of columns 41 and 46, respectively. A pipe 50 carries a pump 51 and connects pipes 60 and 46. Pipe 45 is provided with a heat exchanger 61 disposed in close proximity to column 46. A line 49 connects also with pipe 60 for transfer of bottoms from column 46 to storage or to other disposal, not shown. Line 42 is connected with the feed inlet line 40 for supply of raw feed stock, from a source, not shown.

For operation both columns are filled with liquid propane at desired pressures and temperatures and then oil feed stock is introduced through lines 42 and 40 into column 41. After operation has progressed for a sufficient period of time that the system is in "operational equilibrium" column 41 is filled with two liquid phase, the lower liquid phase 55 being an oil-rich phase containing some propane in solution and an upper phase 56 being liquid propane containing some dissolved oil. Reference numeral 54 refers to the liquid-liquid interface between these

two phases. In the process embodiment practiced in the apparatus illustrated by Figure 2, the interface 54 is intended to be somewhat above the point of feed inlet as represented by pipe 40. It is preferred that this interface be maintained from 2 to 6 feet above the feed inlet point.

In column 46 are also maintained a propane phase 59 containing some dissolved oil and an oil-rich phase 58 containing some dissolved propane. Interface 57 represents a liquid-liquid interface between these two phases. This interface in column 46, in operation, is maintained at a point well down the column, preferably a short distance above the propane inlet line 48.

In the operation of the process embodiment using the apparatus of Figure 2 the oil feed stock to be fractionated passes through line 42 from a source, not shown, on through the feed inlet 40 into the upper portion of the oil-rich phase 55. Oil-rich phase from column 41 is passed through line 45 to a midpoint of tower 46 as feed stock and therein forms an oil-rich phase 58. As in the process embodiment of Figure 1, the oil-rich phase 58 is withdrawn from column 46 and divided into two portions. One portion passes through line 50 under influence of pump 51 into the inlet 40. In this inlet line 40 the cycle oil-rich phase and the raw feed stock are mixed and it is intended that mixing at this point be complete so that a homogeneous oil feed stock enters column 41. A mixing orifice, eductor or other mixing means may be provided if desired.

In order that stripping of propane-soluble oils may be complete or substantially complete, I prefer to maintain a constant temperature throughout the oil-rich phase in column 41. Beginning at the interface 54, I prefer to maintain a temperature gradient throughout the propane-rich phase 56, the top of this phase being at a higher temperature than that of the interface. The increasingly higher temperatures in the propane phase 56 cause precipitation of the more aromatic, naphthenic and higher molecular weight paraffinic materials from solution. As examples of temperature conditions, the top of the column 41 in the region of the heater 52 may be maintained at about 200° F. while the temperature of the propane-rich phase decreases on passing downward to a minimum of about 190° F. at the interface 54. The oil-rich phase is then maintained at about this temperature. The liquid propane added through line 43 is also introduced at about 190° F.

The top of column 41 of Figure 2 is maintained between the temperature limits of 190° and 210° F., the feed point between the limits of 180° and 195° F. and the bottom is maintained at about the feed point temperature. The top of the column 46 is maintained within the temperature limits of 140° to 160° F., the bottom between the limits of 130° to 150° F. The top of the secondary zone 46 is always maintained at a higher temperature than the bottom thereof. Propane is added through line 48 between the volume limits of 6:1 and 10:1, of propane to oil charge stock, and propane is added through line 43 to column 41 between the volume limits of 6:1 and 10:1 of propane to oil feed.

The conditions of operation of the secondary column 46 are substantially the same as for column 21 of Figure 1. Columns 21 and 46 may, of course, also be operated with the phase interface above the feed entry, although this is ordinarily not done.

Specific example

A reduced crude oil stock of about 850° F. initial boiling point is prepared by distillation to remove SAE 10 and SAE 20 stocks. This said reduced crude oil containing all crude components heavier than SAE 20 oil is then fractionated by means of propane to produce SAE 50 and SAE 70 stocks as overhead products and a final asphalt product according to the following sequence of operations.

The reduced crude oil is charged into the propane fractionating column 41 through oil feed lines 42 and 40. The oil feed temperature is about 190° F., the column top temperature about 200° F. and the bottom temperature about 190° F. The column pressure is about 640 pounds per square inch gage. A volume of propane equal to 7 to 8 times the volume of oil charged is introduced through line 43 near the bottom of the column. The propane column is so operated that the continuous phase at the point of oil feed entry is the oil-rich phase 55. The oil-feed entry is near the midpoint of the column. The points of oil entry and propane entry should be so separated that the oil-rich phase may be well stripped of light oils by the propane rising up through the column. A temperature gradient of about 10° F. is maintained for fractionating purposes between the oil feed and the tower top. The stripping section, from the oil inlet to the bottom of the column, is maintained at a constant temperature to facilitate stripping. The overhead fraction from this column comprises a propane solution of SAE 40 to SAE 50 oil depending upon the operating variables of temperature, pressure, and the ratio of propane to oil and is withdrawn through line 44. The bottom product which consists of the propane-insoluble phase forms the oil-rich phase which is withdrawn from the column through line 45. The rate of withdrawal of this phase is adjusted to hold the interface at a constant level in the column and at a point above the oil feed entry.

The oil-rich phase from column 41 is then charged into another propane fractionating column 46 for fractionation into an SAE 70 fraction. This second column 46 is operated at lower temperatures and pressure than the first column. For the preparation of the SAE 70 fraction, the column pressure is about 460 pounds per square inch gage. Additional propane is added through line 48. The oil feed temperature is about 145° F. with the top and bottom tower temperatures at 150° F. and 140° F., respectively. The propane-to-oil ratio is about 8 in column 46. A portion of the bottom product from this column, which is the oil-rich phase and contains very heavy oils and resins, is then recycled through line 50 into propane fractionating column 41. The point of introduction of the oil is located below the interface 54. The amount of oil phase which is recycled depends, of course, upon the stock being treated, and may vary between the limits of 10% and 50% of the oil-rich phase withdrawn through line 60. The remaining bottoms which are not recycled may be drawn off through line 49 and passed to storage, or further fractionated into SAE 70 or SAE 250 oil stocks, as desired.

The increased concentration of heavy oils and resins in the stripping section of column 41 is sufficient to change the phase relationships and prevent the formation of the hard asphaltic phase which plugs the column.

Auxiliary apparatus such as pumps, valves,

temperature measuring and indicating devices, pressure measuring and indicating devices, controls and flow meters, and the like, are not shown or described herein for purposes of simplicity. The installation and operation of such auxiliary equipment is well understood by those skilled in the art. Materials of construction for the apparatus as herein described need not be specific materials since ordinarily corrosion problems are not encountered. The equipment must, however, be so designed and constructed as to withstand the relatively high operating pressures necessitated to keep the propane in the liquid phase at all times. It will be obvious to those skilled in the art that the conditions of operation and other alterations and variations may be made and yet remain within the intended spirit and scope of the invention.

Having disclosed my invention, I claim:

1. In the propane fractionation of lubricating oil constituents from low asphalt-content reduced crude lubricating oil stocks with liquid propane wherein solid asphaltic materials precipitates upon initial contact with the propane and adheres to and plugs the fractionating apparatus in the region adjacent and below the raw feed entry point, a process for continuously carrying out this fractionation operation without precipitating said asphalt and plugging said apparatus comprising maintaining a body of liquid propane containing dissolved oil in a first treating zone, maintaining a body of an oil phase rich in asphalt below said body of propane containing dissolved oil in said zone, said bodies meeting at a common interface, introducing a stream of liquid propane into said body of oil phase rich in asphalt and a stream of said asphalt-containing lubricating oil stock into said body of liquid propane containing dissolved oil at an intermediate point thereof, removing oil phase rich in asphalt from said first zone, removing propane containing dissolved oil from said zone and recovering the oil therefrom as one product of the process; maintaining a second body of liquid propane containing dissolved oil in a second treating zone, maintaining a second body of an oil phase rich in asphalt below said body of liquid propane containing dissolved oil in said second zone, said two bodies meeting at a common interface, introducing liquid propane into said second oil phase rich in asphalt, passing the removed oil phase rich in asphalt from the first zone into an intermediate point of the body of propane containing dissolved oil in said second zone, removing oil phase rich in asphalt from the second zone and passing a portion thereof into the first zone at the feed inlet level of said zone, recovering oil from the remainder of the removed oil phase rich in asphalt from the second zone as a second product of the process, withdrawing propane containing dissolved oil from the second zone and recovering the oil therefrom as a third product of the process.

2. The process of claim 1 wherein the top of the first zone is maintained at a temperature between the limits of 190° and 210° F., the lubricating oil stock feed point is maintained at a temperature between the limits of 180° and 195° F., and the bottom of this zone is maintained at a temperature between the limits of 175° and 190° F., and said first zone is maintained under a pressure greater than the vapor pressure of propane at the highest temperature in said first zone; and wherein the top of the second zone is maintained at a temperature within the limits of

140° to 160° F., the bottom of said second zone is maintained at a temperature between the limits of 130° to 150° F., the top of this second zone is maintained at a higher temperature than the bottom thereof at all times, and said second zone is maintained under a pressure greater than the vapor pressure of propane at the highest temperature in said second zone; and wherein the propane to crude oil ratio in the first zone is maintained between the limits of 6 to 1 and 10 to 1 and the ratio of the propane-to-oil in the second zone is maintained between the limits of 6 to 1 and 10 to 1.

3. The process of claim 2 wherein the proportion of the oil-rich phase from the second zone introduced at the feed inlet level of the first zone is within the limits of 10% to 50% of the oil-rich phase withdrawn from said second zone.

4. The process of claim 3 wherein the pressure maintained in the first zone is 640 pounds per square inch gage and the pressure maintained in the second zone is 460 pounds per square inch gage.

5. In the propane fractionation of lubricating oil constituents from low asphalt-content reduced crude lubricating oil stocks with liquid propane wherein solid asphaltic material precipitates upon initial contact with the propane and adheres to and plugs the fractionating apparatus in the region adjacent and below the raw feed entry point, a process for continuously carrying out this fractionation operation without precipitating said asphalt and plugging said apparatus comprising maintaining a body of liquid propane containing dissolved oil in a first treating zone, maintaining a body of an oil phase rich in asphalt below said body of propane containing dissolved oil in said zone, said bodies meeting at a common interface, introducing a stream of liquid propane into said body of oil phase rich in asphalt and a stream of the asphalt-containing lubricating oil stock into said zone at an intermediate point thereof, removing oil phase rich in asphalt from said first zone, removing propane containing dissolved oil from said zone and recovering the oil therefrom as one product of the process; maintaining a second body of liquid propane containing dissolved oil in a second treating zone, maintaining a second body of an oil phase rich in asphalt below said body of propane containing dissolved oil in said zone, said bodies meeting at a common interface, introducing a stream of liquid propane into said body of oil phase rich in asphalt and a stream of the asphalt-containing lubricating oil stock into said zone at an intermediate point thereof, removing oil phase rich in asphalt from said first zone, removing propane containing dissolved oil from said zone and recovering the oil therefrom as one product of the process; maintaining a second body of liquid propane containing dissolved oil in a second treating zone, maintaining a second body of an oil phase rich in asphalt below said body of liquid propane containing dissolved oil in said second zone, said two bodies meeting at a common interface, introducing liquid propane into said second oil phase rich in asphalt, passing the removed oil phase rich in asphalt from the first zone to an intermediate point of the body of propane containing dissolved oil in said second zone, removing oil phase rich in asphalt from the second zone and admixing a portion thereof with said stream of said asphalt-containing lubricating oil stock prior to its introduction into said first zone at said intermediate point, recovering oil from the remainder of the removed oil phase rich in asphalt from the second zone as a second product of the process, withdrawing propane containing dissolved oil from the second zone and recovering the oil therefrom as a third product of the process.

6. The method of claim 5 wherein said common interface in said first zone is maintained at a point below said intermediate point of said zone.

7. The method of claim 6 wherein the top of

the first zone is maintained at a temperature between the limits of 190° and 210° F., the lubricating oil stock feed point is maintained at a temperature between the limits of 180° and 195° F., and the bottom of this zone is maintained at a temperature between the limits of 175° and 190° F. and said first zone is maintained under a pressure greater than the vapor pressure of propane at the highest temperature in said first zone; and wherein the top of the second zone is maintained at a temperature within the limits of 140° to 160° F., the bottom of said second zone is maintained at a temperature between the limits of 130° to 150° F., the top of this second zone is maintained at a higher temperature than the bottom thereof at all times, and said second zone is maintained under a pressure greater than the vapor pressure of propane at the highest temperature in said second zone; and wherein the propane-to-crude oil ratio in the first zone is maintained between the limits of 6 to 1 and 10 to 1 and the ratio of the propane-to-oil in the second zone is maintained between the limits of 6 to 1 and 10 to 1.

8. The method of claim 7 wherein the proportion of the oil-rich phase from the second zone admixed with the lubricating oil stock and introduced at the midpoint of the first zone is within the limits of 10% to 50% of the oil-rich phase withdrawn from said second zone.

9. In the propane fractionation of lubricating oil constituents from low asphalt-content reduced crude lubricating oil stocks with liquid propane wherein solid asphaltic material precipitates upon initial contact with the propane and adheres to and plugs the fractionating apparatus in the region adjacent and below the raw feed entry point, a process for continuously carrying out this fractionation operation without precipitating said asphalt and plugging said apparatus comprising maintaining a body of liquid propane containing dissolved oil in a first treating zone, maintaining a body of an oil phase rich in asphalt below said body of propane containing dissolved oil and in said zone, said bodies meeting at a common interface, introducing a stream of liquid propane into said body of oil phase rich in asphalt and a stream of said asphalt-containing lubricating oil stock into said body of oil phase rich in asphalt at a midpoint of said zone, removing oil phase rich in asphalt from said first zone, removing propane containing dissolved oil from said zone and recovering the oil therefrom as one product of the process; maintaining a second body of liquid propane containing dissolved oil in a second treating zone, maintaining a second body of an oil phase rich in asphalt below said body of liquid propane containing dissolved oil and in said second zone, said two bodies meeting at a common interface, introducing liquid propane into said second oil phase rich in asphalt, passing said removed oil phase rich in asphalt from the first zone into an intermediate point of the body of propane containing dissolved oil in said second zone, removing oil phase rich in asphalt from the second zone and passing a portion thereof into the first zone near the feed inlet level of said zone, recovering oil from the remainder of the removed oil phase rich in asphalt from the second zone as a second product of the process, withdrawing propane containing dissolved oil from the second zone and recovering the oil therefrom as a third product of the process.

10. In the propane fractionation of lubricating

oil constituents from low asphalt-content reduced crude lubricating oil stocks with liquid propane wherein solid asphaltic material precipitates upon initial contact with the propane and adheres to and plugs the fractionating apparatus in the region adjacent and below the raw feed entry point, a process for continuously carrying out this fractionation operation without precipitating said asphalt and plugging said apparatus comprising maintaining a body of liquid propane containing dissolved oil in a first treating zone, maintaining a body of an oil phase rich in asphalt below said body of propane containing dissolved oil in said zone, said bodies meeting at a common interface, introducing a stream of liquid propane into said body of oil phase rich in asphalt and a stream of said asphalt-containing lubricating oil stock into said body of liquid propane containing dissolved oil at an intermediate point thereof, removing oil phase rich in asphalt from said first zone, removing propane containing dissolved oil from said zone and recovering the oil therefrom as one product of the process; maintaining a second body of liquid propane containing dissolved oil in a second treating zone, maintaining a second body of an oil phase rich in asphalt below said body of liquid propane containing dissolved oil in said second zone, said two bodies meeting at a common interface, introducing liquid propane into said second oil phase rich in asphalt, passing said removed oil phase rich in asphalt from the first zone into an intermediate point of the body of propane containing dissolved oil in said second zone, removing oil phase rich in asphalt from the second zone and passing a portion thereof into the first zone near the feed inlet level of said zone, recovering oil from the remainder of the removed oil phase rich in asphalt from the second zone as a second product of the process, withdrawing propane containing dissolved oil from the second zone and recovering the oil therefrom as a third product of the process.

11. In a process for the fractionation of a lubricating oil stock containing some asphalt with liquid propane wherein a deposit of asphalt is formed and adheres to and plugs the fractionating apparatus, a method for carrying out said fractionation without deposition of asphalt comprising maintaining a body of liquid propane containing dissolved oil in a first treating zone, maintaining a body of an oil-rich phase below said body of propane containing dissolved oil in said zone, said bodies meeting at a common interface, introducing a stream of liquid propane into said body of oil-rich phase and a stream of the asphalt-containing lubricating oil stock into said zone at an intermediate point thereof and below said common interface, removing oil-rich phase from said first zone, removing propane containing dissolved oil from said zone and recovering the oil therefrom as one product of the process; maintaining a second body of liquid propane containing dissolved oil in a second treating zone, maintaining a second body of an oil-rich phase below said body of liquid propane containing dissolved oil in said second zone, said two bodies meeting at a common interface, introducing liquid propane into said second oil-rich phase, passing said removed oil-rich phase from the first zone to an intermediate point of the body of propane containing dissolved oil in said second zone, removing oil-rich phase from the second zone and admixing a portion thereof with said

15

stream of said asphalt-containing lubricating oil stock prior to its introduction into said first zone at said intermediate point, recovering oil from the remainder of the removed oil-rich phase from the second zone as a second product of the process, withdrawing propane containing dissolved oil from the second zone and recovering the oil therefrom as a third product of the process.

12. The method of claim 11 wherein the top of the first zone is maintained at a temperature between the limits of 190° and 210° F., the lubricating oil feed point is maintained at a temperature between the limits of 180° and 195° F., and the bottom of this zone is maintained at the same temperature as that of said feed point, and said first zone is maintained under a pressure greater than the vapor pressure of propane at the highest temperature in said first zone; and wherein the top of the second zone is maintained at a temperature within the limits of 140 to 160° F., the bottom of said second zone is maintained at a temperature between the limits of 130° to 150° F., the top of this second zone is maintained at a higher temperature than the bottom thereof at all times, and said second zone is maintained under a pressure greater than the vapor pressure

5

16

of propane at the highest temperature in said second zone; and wherein the propane-to-lubricating oil stock ratio in the first zone is maintained between the limits of 6:1 and 10:1 and the ratio of the propane-to-lubricating oil stock in the second zone is maintained between the limits of 6:1 and 10:1.

13. The method of claim 12 wherein the proportion of the oil-rich phase from the second zone introduced at the feed inlet level of the first zone is within the limits of 10% to 50% of the oil-rich phase withdrawn from said second zone.

14. The method of claim 12 wherein the pressure maintained in the first zone is 640 pounds per square inch gage and the pressure maintained in the second zone is 460 pounds per square gage.
